UNITED STATES PATENT OFFICE.

ALICE K. MATTULLATH, OF INWOOD, NEW YORK, ASSIGNOR TO AMERICAN BALSA CORPORATION, OF NEW YORK, N. Y., A CORPORATION OF NEW YORK.

DIRIGIBLE AIRSHIP.

1,376,629.

Specification of Letters Patent.

Patented May 3, 1921.

Application filed April 10, 1918. Serial No. 227,632.

To all whom it may concern:

Be it known that I, ALICE K. MATTULLATH, a citizen of the United States, residing in Inwood, county of Nassau, and State of New York, have invented certain new and useful Improvements in Dirigible Airships, of which the following is a specification.

This invention relates to dirigible airships of the rigid type and has for its objects the production of an airship in which the outer envelop consists essentially of a non-metallic, substantially rigid, non-splintering, cellular, heat-insulating medium, possessing considerable strength and elasticity and withal being waterproof, extremely light and buoyant in water.

I am aware that heretofore aluminum envelops have been proposed which were provided with numerous compartments adapted to contain ballonnets, *i. e.*, small balloons which were filled to the desired pressure with hydrogen or other suitable gas. Obviously, the object of such sub-division was to prevent the collapse of the entire structure if a portion of the envelop and one or more compartments were destroyed by shell or rifle fire, or from collision or otherwise. While such a type of dirigible has many advantages, it also has certain decided disadvantages which it is the object of this invention to eradicate. Chief among these objections is the high co-efficiency of heat transmission of aluminum, it being, as is well known, an excellent conductor of heat. Accordingly, as a dirigible having an aluminum envelop passes from lower to higher altitudes or vice versa, there is a corresponding shrinkage or expansion of the gas field with a consequent variation of the buoyancy. Furthermore, in the event of the exhaustion of the gas, such a dirigible is so heavy as to sink when a landing upon water is necessitated. These and many other objections are overcome by my improved dirigible which is fully set forth and described in the accompanying specification and drawings forming a part thereof, in which—

Figure 1 is a longitudinal elevation of my improved dirigible, a portion being shown in section;

Fig. 2 is a transverse section along the line 2—2 of Fig. 1;

Fig. 3 is an enlarged detail fragmentary section of the outer envelop showing the bracing therefor.

Referring to the drawings and the construction shown therein, the reference numeral 1 designates the outer, rigid, sectional envelop of artificially preserved and waterproofed balsa wood which is adapted to completely envelop or contain the gas-field of the dirigible. The envelop is made up of a plurality of separate strips, preferably having from 20 to 24 facets, each of which is bolted to a skeleton angle iron frame as hereinafter described. The dirigible is provided with one or more cars, as designated by the numeral 2, which are adapted to contain the power plant, including propelling mechanism, as well as the necessary fuel, ballast, crew, radio-apparatus, etc. It is also equipped with one or more, vertical rudders 3, vertical fins 4, 4', and horizontal fins 5, 5', elevating devices 6 (the one on the opposite side not being shown) all of which are customary and well known in the art and not specifically claimed herein.

The entire envelop is preferably sub-divided by radial, longitudinal partitions 8, 8' and 9, 10, 10' into sub-compartments *a*, *b*, *c*, *d* and *e*. Two transverse vertical partitions 7, 7', preferably also of balsa wood, form a central compartment immediately above the car. The latter compartment is provided with a floor of any suitable flooring material 11, which is provided with suitable trap door or other means of access, (not shown). The said sub-division of the envelop by the radial partitions insures against the destruction of the dirigible in the event a portion of the envelop is destroyed by shell fire or otherwise, since each compartment will contain a separate gas-field that is adapted to be supplied with hydrogen through a supply pipe (not shown) common to all the individual compartments. Such pipe is provided with valves (not shown) for preventing the escape of the gas from any single compartment in the event of destruction of the adjacent compartment, provided of course also such compartments remain intact. However, such sub-division of the envelop into compartments forms no part of my invention.

Each of the compartments into which the envelop is divided is preferably provided with separate ballonnets made of fabric commonly known as balloon-cloth, although if the joints between the balsa wood sections of the outer envelop are lined with a cem-

entious coating capable of rendering the entire inner surface and joints gas tight, the outer envelop itself will be sufficiently impervious to permit of the balloon-cloth ballonnets being dispensed with, and in such cases the gas in each compartment contacts directly with the lining of the outer balsa wood envelop. Owing to the great strains to which dirigibles are subjected, I preferably, as aforesaid, however employ balloon cloth ballonnets in each compartment, filling the same in the customary manner from a central generating station.

Balsa wood (*Ochroma lagopus*), which is the material from which I preferably construct the outer envelop of the dirigible, grows extensively in Costa Rica and other Central and northern South American States as a second-growth tree. It has a S. G. of about .25 and is believed to be the lightest wood that is commercially used. It is composed of very thin-walled cells, which are barrel-shaped, interlace with each other, and are almost devoid of woody fiber. These cells are filled with air, making a natural structure well adapted to prevent the transmission of heat, because of the particles of air imprisoned in the material without interconnecting fibers. Unless encysted or otherwise treated with a suitable preservative its life under ordinary conditions is extremely short. The ordinary commercial balsa wood which is seldom perfectly dry weighs between 8 and 13 lbs. per cubic foot, when thoroughly dried but 7.3 lbs. per cubic foot, whereas Missouri cork wood, one of the lightest varieties of cork, weighs approximately 18.1 lbs. per cubic foot. Said balsa wood is also remarkably free from woody fibers. It is extremely elastic in so far as recovery against transverse deformation is concerned. It is unusually strong, its crushing strength approximating one-half that of white pine or spruce. Furthermore, it is almost impossible to split or splinter the wood by driving nails or shooting bullets through it. It also has an extremely low-efficient of heat transmission, for example, as tested by the Bureau of Standards, the co-efficient of heat transmitted through balsa wood per inch of thickness is 5.98 or in other words 5.98 British thermal units, per degree Fahr. of difference in temperature of the air on the two sides, are transmitted through balsa wood one inch in thickness in a period of 24 hours.

Balsa wood has been satisfactorily preserved by encysting the cells with paraffin in such a manner that the interior cells were coated without entirely clogging up the cellular system since the paraffin remains only as a coating or varnish on the interior cell walls. Such coating prevents the absorption of moisture and the change of volume and decay which would otherwise take place,

besides preventing the bad effects of dry rot which often accompanies superficial treatment of wood of this type. In such treatment the water normally present in the wood is driven off, the wood is made waterproof, its quality of being readily worked with tools is greatly improved and its weight is not materially increased since the added paraffin replaces principally the water which has been driven off. Such waterproofing which is described in detail in the Patents to R. A. Marr, No. 1,121,644 of December 22, 1914 and Reissue No. 13,952 of July 27th, 1915, and constitutes no part of my invention, as herein set forth, is especially adapted for the treatment of balsa wood intended for the construction of the herein described envelop. Such envelop may be further strengthened, if desired, by covering the outer surface, or if desired both the outer and inner surface, with a waterproof skin of tough paper, canvas, or other suitable textile material so as to form a smooth continuous hard shell, thereby lessening the air-resistance of the envelop, as well as making it possible to dispense entirely with a lining of balloon cloth or with individual ballonnets confined in the separate compartments. Such coverings for both the inner and outer surfaces are specifically shown in Fig. 3 and are indicated by the reference characters 12 and 13 respectively.

Having thus described my invention, what I claim and desire to secure by Letters Patent is:—

1. A substantially gas-tight gas envelop for containing the main buoyant gas field of dirigible airships comprising a skeleton-frame embodying a relatively hard and tough material, and walls which are principally composed of an extremely soft, elastic and porous wood of extremely low specific gravity, the pores of which have been lined or encysted throughout by a suitable preservative and waterproofing material, whereby a gas envelop is provided having extreme lightness, a high degree of buoyancy in water, durability, and high heat insulating and non-splinterable properties.

2. A substantially gas-tight gas envelop for containing the main buoyant gas field of dirigible airships comprising a skeleton-frame embodying a relatively hard and tough material, and walls which are principally composed of balsa wood having its pores lined or encysted throughout by a suitable preservative and waterproofing material.

3. A substantially gas-tight gas envelop for containing the main buoyant gas field of dirigible airships comprising a shell having a skeleton-frame embodying a relatively hard and tough material and having its walls principally composed of balsa wood pieces which have been treated to cause the

- pores thereof to be lined or encysted throughout by a suitable preservative and waterproofing material, and which balsa wood pieces are suitably joined together and 5 reinforced by a suitable adherent surface covering to form a continuous surface.
4. A substantially gas-tight gas envelop for containing the main buoyant gas field of dirigible airships, comprising a shell having a skeleton-frame embodying a relatively hard and tough material, and having its 10 walls principally composed of balsa wood pieces which have been treated to cause the pores thereof to be lined or encysted throughout by a suitable preservative and 15 waterproofing material, and which balsa wood pieces are suitably joined together and reinforced by a tough adherent outer covering and having an inside lining of a suitable gas-proof material. 20
- In witness whereof, I have hereunto set my hand at New York, county and State of New York, this 4th day of April, 1918.

ALICE K. MATTULLATH.
